Nathan Bracy & Edward P. Bracy, Complts.

Letter Patent.

The Schedule referred to in these Letter Patent and making part of the same, containing a description in the words of the said Nathan Bracy & Edward P. Bracy themselves, of their improvement in the mode of making or manufacturing Pill Boxes.

To all Persons to whom these shall come,
Nathan Bracy of New York and Edward P. Bracy of the Town of Bronx,
both of the County of Bronx State of New York, and, Declaring,
Be it known that we the said Attorneys Edward P. Bracy inven-
ted, constructed, and applied to use, a new & useful improve-
ment in the mode of making or manufacturing Pill Boxes or
the small circular or oval boxes, commonly known & distinguished
by their name to whatever purpose applied, which improvement
consists in the construction, application & use of the rollers or
the splitting gauge. The said plate & the pins, specified in the
words following:— The rollers are solid cylinders of wood, of a
convenient length, of which rollers one is required for the bodies
one for the covers of boxes of the same size, & which rollers at their
circular surface, are respectively of a diameter equal to that of
the inner part of the bodies of the boxes of the bodies of the
covers respectively and arranged which rollers the bodies
of the boxes and their covers are respectively arranged to be placed
or fastened. If the boxes to be manufactured are to be divided
of boxes, the rollers have a flat surface instead of the circular
one, number of these rollers is required equal to the number of the
boxes plus the number of boxes bodies which are in proportion of
giving or fastening at the same time. The splitting gauge is a
plate of wood of convenient size with two flat surfaces

etc.

it might very conveniently be cut out of a piece of wood, for one piece of wood is a parallelopiped, in the angle formed by which said surfaces an excavation or cutting is made down in a line at the surface of flat at the other surface of the said excavation, the last mentioned surface being at right angles with each other, and the lower or bottom face of said excavation is of a diameter equal to a little greater than that of the bodies of the box covers respectively of small printed stills or specie in almost this, said piece of wood, so as to project up into the circular surface of said excavation, parallel to the flat surface, & just as far from it as the intended width of the body of a box cover. The use of the splitting gauge is to cut a shaving or other suitable substance for the body of a box cover into two equal parts. For this purpose the shaving being wound round the roller as above described, & glued or fastened the roller with the shaving round it, at one end of it is placed in the excavation in the splitting gauge & being turned round on its circular surface, the shaving is cut by the blade into two equal parts, suitable for the covers of two boxes. — The Steel Plate is a thin plate of tempered steel of about one eighth of an inch in thickness, the which is made circular holes of a rather larger circumference at the lower surface than at the upper one, so that the plate at its upper surface presents a blunt edge, round the circumference of the holes. These at their smallest circumference should be precisely equal to that of which the rollers respectively are required to be made. There should be one hole for the roller for the body and one for those of the bodies of covers for the manufacture of boxes of one size — of the largest to be manufactured are to be round instead of round, the holes in the plate must be made of a size corresponding thereto — These holes in the plate, together with the round or blunt pieces of wood

the following is a copy of a letter from the State of New
Mexico to the State of Colorado concerning the return of
game to places of origin and the right of a state
to regulate its own game.

The simple mechanics of wood or
iron for your basket are well suited for the protection
of a savage life & nothing larger at the top of the basket
is necessary at the bottom than the diameter of the box
bottom or the outer basket is fastened to it which
will stop the box bottom & lower basket being wound in
around the bottom & glued are respectively placed or
united to day.

interesting that the above is a true
specification of an old improvement & that the Indians
in have used it to set our traps & traps this trout fish
would be caught in the year of our Lord one thousand
and one hundred & thirty.
